[57] CLAIM

I claim the ornamental design for a doll, as shown.

DESCRIPTION

FIG. 1 is a left side perspective view of the doll with a number of personal accessories, shown in phantom, attached to the hands and feet, the accessories forming no part of the claimed design;

FIG. 2 is a front elevation thereof;

FIG. 3 is a rear elevation thereof;

FIG. 4 is a right side view thereof;

FIG. 5 is a left side view thereof;

FIG. 6 is a top view thereof;

FIG. 7 is a bottom plan view thereof; and,

FIG. 8 is a right side perspective view thereof.
